UNITED STATES PATENT OFFICE.

CARL GUSTAV THEODOR JACOBSON, OF EVELETH, MINNESOTA.

SAW-HANDLE.

1,149,061.

Specification of Letters Patent.

Patented Aug. 3, 1915.

Application filed September 14, 1914. Serial No. 861,693.

To all whom it may concern:

Be it known that I, CARL GUSTAV THEODOR JACOBSON, a citizen of the United States, residing at Eveleth, in the county of St. Louis and State of Minnesota, have invented certain new and useful Improvements in Saw-Handles, of which the following is a specification, reference being had to the accompanying drawings.

10 This invention comprehends certain new and useful improvements in wood working tools, and relates particularly to a detachable saw handle.

The invention has for its primary object a simple, durable and efficient construction of device of this character, the parts of which may be very cheaply manufactured and readily assembled and which may be very quickly applied to and detached from 20 the saw blade. And the invention also aims to generally improve devices of this class so as to render them more useful and commercially desirable.

With these and other objects in view, as 25 will more fully appear as the description proceeds, the invention consists in certain constructions, combinations and arrangements of the parts that I shall hereinafter more fully describe and claim.

30 For a full understanding of the invention, reference is to be had to the following description and accompanying drawing, in which—

Figure 1 is a sectional side elevation of a 35 portion of a saw having my improved detachable handle connected to the blade thereof. Fig. 2 is a detail view of the attaching bar. Fig. 3 is a fragmentary transverse section on the line 3—3 of Fig. 1. Fig. 4 is 40 a similar view of the device on the line 4—4 of Fig. 1.

Corresponding and like parts are referred 45 to in the following description and designated in all of the views of the accompanying drawing by like reference characters.

Referring to the drawing, the numeral 1 designates the blade of a saw and 2 the handle proper, these parts being of any desired construction or design, except as 50 hereinafter noted.

Secured to the upper edge of the handle 2 is an attaching bar 3 which is secured to the handle in any desired way and which is preferably constructed of a single strip of 55 metal extending any desired distance be-

yond the forward end of the handle. As it leaves the handle 2, the metal out of which this attaching bar is formed is doubled upon itself longitudinally to form a channeled portion 4 designed to receive the upper 60 edge of the saw blade 1, and this channeled portion terminates at the forward extremity of the bar 3 in a lug 5 which extends laterally from both sides of the channel portion. The channel 6 of the portion 4 of the 65 attaching bar 3 communicates with a recess 7 which is formed in the handle 2, the said recess being designed to receive one end of the saw blade and secured to the handle 2 and extending across the recess 7 is a stud 70 8 which is designed to fit within an obliquely disposed notch 9 formed in one end of the blade. The lug 5 is designed to engage a notch 10 in the upper edge of the blade.

From the foregoing description in connection with the accompanying drawing, the 75 operation of my device will be apparent. In the practical use of my improved detachable handle, the handle proper 2 is slipped over one end of the blade 1 and the 80 stud 8 is received in the notch 9 and the channel portion 4 of the attaching bar 3 is extended over and receives the upper edge of the blade 1, the bar being somewhat resilient and the lug 5 is snapped down into 85 the notch 9, whereupon the handle will be securely attached to the blade, or may be readily detached therefrom when desired. In order to detach the blade, it is only necessary to press upwardly on the laterally disposed lug 5 so as to move it outwardly from 90 the notch 10 and swing the handle to a somewhat oblique position relative to the blade, whereupon the attaching bar will be entirely free from the blade and the handle 95 can be readily withdrawn by slipping the stud 8 out of the notch 9.

While the accompanying drawing illustrates what I believe to be the preferred embodiment of my invention, it is to be understood that the invention is not limited in this regard, but that various changes may be made in the details of construction, arrangement and proportions of the parts without departing from the scope of the invention as defined in the appended claims.

What is claimed is:

1. A saw handle having one end formed with a vertically extending kerf adapted to receive the butt end of a saw blade, a stud 110

extending through the handle and across said kerf, said stud being disposed at the lower end of the kerf, a resilient saw engaging member mounted upon the upper edge 5 face of the handle and extending in advance thereof and having a downwardly extending lug adjacent its ends, and a saw blade formed on its rear edge with a notch adapted to engage said stud when the rear edge is 10 inserted into the kerf, the handle when the blade is so inserted bearing against the rear edge of the saw below the stud, said blade also having upon its upper edge a notch adapted to receive a lug formed in the upper 15 edge of the attaching member.

2. A saw handle having a vertically extending kerf in one end adapted to receive the rear end of a saw blade, a stud extending through the handle and across said kerf 20 and disposed above the lower end of the kerf, a saw engaging member mounted upon the upper edge of the handle and extending in advance thereof, said member being formed of a resilient strip channeled upon 25 its under face to receive the upper edge of a saw blade and being formed at its extremity with a depending lug, and a saw blade formed on its rear edge with a notch adapted 30 to engage the stud when the butt end of the saw blade is inserted in the kerf and formed upon its upper edge with a notch adapted to receive said lug.

3. A saw comprising a blade formed in its upper edge forward of its butt end with a 35 notch and at its inner end with an upwardly and forwardly extending slot and a handle formed on one end with a vertically extending kerf whereby it is adapted to be slipped upon the butt end of the blade, a stud extending through the handle and across said 40 kerf and adapted to engage the upper end of said slot when the upper edge of the saw blade is alined with the upper edge of the handle, the butt end of the saw blade engaging 45 with the inner wall of the kerf above and below a line extending parallel to the back of the saw blade and passing through said stud, and a resilient blade engaging member mounted upon the upper end of the 50 handle and having a forwardly extending portion adapted to engage the upper edge of the blade, said member being provided at its forward extremity with a depending lug inserrible within the notch in the upper edge

of the blade and locking the blade to the 55 handle.

4. A saw comprising a blade, a handle on the blade having a notch formed in its upper end forward of the butt end of the blade, the butt end of the blade being formed with a 60 slot, a handle having a vertically extending kerf adapted to receive the butt end of the blade, a stud extending transversely across the kerf and adapted to engage in the slot in the blade, and a blade engaging member 65 mounted upon the upper edge of the handle and extending in advance thereof and having a lug adapted to engage the notch in the upper edge of the blade, formed with lateral flanges extending from the handle to 70 said lug and adapted to embrace the blade along its entire upper edge.

5. A saw comprising a blade having a notch in its upper end spaced from the butt end of the blade and formed at its butt end 75 with an upwardly and forwardly extending slot and a handle formed with a vertically extending kerf adapted to receive the butt end of the blade, the inner wall of the kerf bearing against the rear end of the blade 80 below said slot in the blade, a stud extending through the handle and across said kerf and adapted to engage the upper end of the slot when the butt of the blade is abutted against the rear wall of the kerf, and a resilient blade engaging member comprising a strip having a flat rear portion bearing 85 against the upper end of the handle and attached thereto, the forward portion of the strip extending beyond the handle and being 90 U-shaped in cross section to fit around the upper end of the saw blade, the forward end of the strip having a downwardly extending lug to engage in the notch in the upper end of the blade, the butt end of the 95 blade, when in position in the handle and when the blade is engaged by said strip, bearing against the rear wall of the kerf above and below a line extending through the stud and approximately parallel to the 100 back of the blade.

In testimony whereof I hereunto affix my signature in the presence of two witnesses.

CARL GUSTAV THEODOR JACOBSON.
